US00D811246S

(12) **United States Design Patent** (10) Patent No.: **US D811,246 S**
(45) Date of Patent: **** Feb. 27, 2018**

(54) **DRAWING RULE**

(71) Applicant: **MAPED**, Argonay (FR)

(72) Inventor: **Sylvain Lopez**, Brison Saint Innocent (FR)

(**) Term: **15 Years**

(21) Appl. No.: **35/502,022**

(22) Filed: **Nov. 10, 2016**

(80) **Hague Agreement Data**

Int. Filing Date: **Nov. 10, 2016**

Int. Reg. No.: **DM/093505**

Int. Reg. Date: **Nov. 10, 2016**

Int. Reg. Pub. Date: **Dec. 2, 2016**

(51) **LOC (11) Cl. 10-04**

(52) **U.S. Cl.**

USPC **D10/64**

(58) **Field of Classification Search**

USPC D10/64, 62

CPC B43L 7/005; B43L 13/201; B43L 13/205;

G01B 3/563
